CLAIM

The ornamental design for a cable holder as shown and described.

DESCRIPTION

FIG. 1 is a perspective view of a cable holder in an open configuration showing our new design.

FIG. 2 is a back view thereof.

FIG. 3 is front view thereof.

FIG. 4 is a left side view thereof.

FIG. 5 is a right side view thereof.

FIG. 6 is a top view thereof.

FIG. 7 is a bottom view thereof.

FIG. 8 is a perspective view of the cable holder in a closed configuration showing our new design.

FIG. 9 is a back view thereof.

FIG. 10 is a front view thereof.

FIG. 11 is a left side view thereof; and,

FIG. 12 is a bottom view thereof.

The broken lines shown in the Figures represent portions of the cable holder that form no part of the claimed design. The article is shown with a symbolic break in its length. The appearance of any portion of the article beyond the break lines forms no part of the claimed design. The dash-dot break lines form no part of the claimed design.
